CLAIM

The ornamental design for a food storage container, as shown and described.

DESCRIPTION

FIG. 1 is a perspective view of a food storage container in accordance with the present invention;

FIG. 2 is an enlarged front top perspective view thereof;

FIG. 3 is an enlarged rear top perspective view thereof;

FIG. 4 is an enlarged front bottom perspective view thereof;

FIG. 5 is an enlarged rear bottom perspective view thereof;

FIG. 6 is a front view thereof;

FIG. 7 is a rear view thereof;

FIG. 8 is a left view thereof;

FIG. 9 is a right view thereof;

FIG. 10 is a top view thereof; and,

FIG. 11 is a bottom view thereof.

In the drawings, the evenly-spaced broken lines show portions of a food storage container that form no part of the claim; the dash-dot-dash lines represent the frame of the enlarged view and form no part thereof.
